UNITED STATES PATENT OFFICE.

NICHOLAS A. ACKER, OF OAKLAND, CALIFORNIA, ASSIGNOR TO AMERICAN CAN COMPANY, OF NEW YORK, N. Y., A CORPORATION OF NEW JERSEY.

METHOD OF LINING CAN ENDS.

1,336,013.

Specification of Letters Patent.

Patented Apr. 6, 1920.

Application filed March 30, 1917. Serial No. 158,702.

To all whom it may concern:

Be it known that I, NICHOLAS A. ACKER, a citizen of the United States, residing at Oakland, in the county of Alameda and

5 State of California, have invented certain new and useful Improvements in Methods of Lining Can Ends, of which the following is a specification.

The present invention relates to a method 10 of applying gasket liners to can ends and to provide packing material at the seam between the can end and the can body.

In the so-called sanitary type of cans as used principally for the preservation of 15 food products the can ends are united to the can body by having adjacent flanges interfolded to form a seam, and suitable packing material is interposed between the adjacent flanges of the end and the body to 20 form a tight and permanent seal. Practice has demonstrated that the most satisfactory 25 form of packing material consists of a ring liner of paper or other similar fibrous material loosely applied to the flange of the can end before said end is placed upon the can body.

The ring liners forming the packing material between the can end and the can body have heretofore been cut as annular rings 30 by a suitable die from a blank or web or sheet of the liner material, usually paper. Under this method of forming ring liners, there is considerable waste, for although a number of liners of successively smaller diameters can be cut from a single blank, there is necessarily a core, stamped out from 35 the smallest innermost liner, which is wasted; and in addition, there is inevitable waste around the outside of the largest liner cut 40 from the blank.

The object of the present invention is to provide a method of lining can ends from a continuous strip of liner material. By so doing, practically all waste is eliminated, 45 inasmuch as the liner material is made and received in the form of a continuous strip of the proper width for application to the flange of the can end. Moreover, a continuous strip of liner material can be applied 50 to the can end flange by comparatively simple and inexpensive mechanism without danger of mutilation. The elimination of waste not only reduces the cost of lining the can ends by a direct saving of mate-

rial, but also reduces the total amount of 55 liner material handled, thus reducing the transportation and other charges incident thereto.

In its preferred form my invention comprises a method of lining can ends with a 60 continuous strip of liner material, said strip being supplied in the form of a helix having a diameter equal to the diameter of the flange of the can end. It is not my intention however, to limit myself to this form 65 of liner material, but to include other forms capable of supplying the material as a continuous strip. Broadly stated, the invention comprises a method of feeding a continuous strip of liner material to the flanges 70 of can ends to form in each flange an annular gasket liner, and I am aware that any suitably constructed machine may be employed.

In the accompanying drawings is illustrated 75 a preferred form of apparatus for carrying out the various steps of my process, in which,

Figure 1 is a perspective view of the complete apparatus, and

Fig. 2 is a longitudinal section taken on a plane represented by the line 2—2 of Fig. 1.

In the drawings, the reference numeral 1 designates a base or bed-plate which is 85 shown as supported by suitable legs 2. Mounted upon the base 1 are journal brackets 3, which support a horizontally disposed drive shaft 4 having upon its outer end a pulley 5 adapted to receive power from an 90 outside source not shown in the drawings. A clutch is interposed between the pulley 5 and the drive shaft 4 to permit said pulley to run idly upon said shaft. This clutch comprises a dog 6, suitably mounted in the 95 drive shaft and pressed outwardly by a spring 7 to engage any one of a series of notches 8 formed in the hub 9 of the pulley 5. A finger 10 carried by a lever arm 11 is adapted to be moved into a position to engage the dog 6 at a certain point in its rotation and by such engagement to depress said dog to free the same from the hub 9 of the pulley 5. The outer end of the lever arm 11 is connected with a lineally movable 100 rod 12 provided at its end with a handle 13, and normally held in an outward position by a spring 14. The spring 14 holds the parts

in position to cause the finger 10 to lie in the path of the dog 6, and thereby free the same from the hub 9 in the pulley 5. Thus when the rod 12 is temporarily moved inwardly 5 by the operator, the finger 10 is carried out of engagement with the dog 6 and said dog is thereby caused to engage one of the notches 8 of the pulley hub 9. The shaft 4 then rotates with the pulley 5 for one revolution or until the dog 6 again passes under the finger 10, which has in the meantime 10 been returned to its normal position by the spring 14, and thereby disconnects said shaft 4 from the pulley 5. Thus at each operation 15 of the handle 13 the shaft 4 makes one complete revolution, at the end of which it stops.

The shaft 4 carries, between the journals 3, a bevel gear 15 which meshes with and drives a similar gear 16 mounted upon a 20 short vertical shaft journaled in the base 1 at 17. A spur gear 18 is mounted upon said shaft below the bevel gear 16 and meshes with and drives an idler gear 19 similarly journaled in the base 1 at 20. Said idler 25 gear in turn meshes with and drives a third spur gear 21 mounted upon a short vertical shaft journaled in the base 1 at 22. The upper face of the spur gear 21 is formed as a can end chuck to carry and to rotate the can 30 end 23 to be lined. The can end 23 thus rotates continuously during the cycle of operations, the gearing being so proportioned as to impart to said can end a little over one complete revolution during one revolution 35 of the drive shaft 4.

Positioned above the can end 23 and in axial alignment therewith is a mandrel 24 adapted to carry the liner material in the form of a continuous closely wound helix 25, 40 whose diameter is equal to the diameter of the flange of the can end 23 into which the liner is to be placed. The mandrel 24 is mounted upon a vertical shaft 26 which extends through and has a bearing in a bracket 45 27 supported above the base 1. The bracket 27 carries a fixed plate 28 which lies immediately beneath the mandrel 24 and which has an outside diameter equal to or greater than the outside diameter of the helix of liner 50 material 25. Immediately below said fixed plate 28 a bevel gear 29 is mounted upon the vertical mandrel shaft 26 and meshes with and is driven by a similar bevel gear 30 mounted upon the end of the drive shaft 4.

55 The fixed plate 28, which lies immediately beneath the helix carrying mandrel 24, and upon which the helix 25 of liner material rests, is formed with a helical slot or groove 31 in its peripheral region through which 60 the liner material is passed. The upper face of the bevel gear 29 is formed with a beveled surface 32 upon which the liner material rests and by which it is carried after passing through the slot 31 in the fixed plate 28. 65 A similar beveled flange 33 is formed upon

the shaft 4 immediately back of the end bevel gear 30, and the liner strip, after passing approximately three-fourths of the way around the beveled surface 32, is transferred to the beveled surface 33 and follows the 70 same forwardly and downwardly. It is understood that the beveled surfaces 32 and 33 are properly formed to permit the liner strip to lie flat thereupon without lateral bending or breaking. A feed roll 34, 75 adapted to coact with the beveled flange 33, and to feed the liner strip between itself and said beveled flange is mounted upon a horizontal shaft 35 positioned parallel with the shaft 4 and driven therefrom at the 80 proper speed by means of a pair of gears 36 and 37. The liner strip, illustrated at 25^a in Fig. 1 of the drawings, after passing between the feed roll 34 and the beveled flange 33, passes through a fixed guide 38 which 85 guides said liner strip into a proper position for feeding into the flange of the can end 23 resting upon the gear 21. A presser roll 39 is positioned to bear upon said liner strip 25^a and to press the same into the flange of 90 the can end 23. Said presser roll is mounted upon a shaft journaled within a bracket 40 and carrying on its outer end a bevel gear 41 adapted to mesh with and be driven by a similar gear 42, mounted upon a third horizontal shaft 43, journaled in suitable brackets 44. A pair of spur gears 45 and 46 mounted respectively upon said third shaft 43 and the main drive shaft 4 impart motion to said third shaft 43 and thereby cause 95 the presser roll 39 to rotate at the proper speed to lay the liner strip within the flange of the can end 23. 100

The bracket 40 which carries the presser roll shaft is pivotally mounted at 47 upon the end of the horizontal shaft 43, and is connected by means of a downwardly projecting lug 48 with one arm of a bell-crank 49 whose other arm is connected by a link 50 and a lever 51 with a rock-shaft 52 carried in a journal 53 supported by the base 1. The other end of the rock-shaft 52 carries a lever arm 54, upon whose end is mounted a cam following roller 55 adapted to lie within and follow a groove 56 formed in a cam member 57 mounted upon the shaft 43. By means of the mechanism just described the presser roll 39 is lifted out of contact with the can end flange at the end of each cycle of operations, to permit the can end to be removed from its chuck and an unlined end to be placed thereupon. Immediately upon the beginning of the cycle of operations the presser roll 39 is moved downwardly into contact with the liner strip to press the same into the can end flange, and is held in this position until the complete liner is applied. 115

The shaft 43 carries a second cam member 58 in whose face is formed a cam groove 59, which actuates, by means of a roller 60, 120

a sliding plunger 61 carrying on its end a knife 62 adapted to cut the liner strip within the curved guide 38. The cam groove 59 is so formed that the liner strip 25^a is cut at the proper time to supply the requisite length of strip for the lining of the can end. After the strip 25^a has been cut, the cut end portion of the same is fed into the can end flange by the presser roll 39 and the end of the uncut portion of said strip is advanced at the same speed by the feed roll 34 into a position in readiness to be applied to the succeeding can end.

I prefer to unite the ends of the liner strip together after the same has been severed and placed within the can end flange to form a continuous annular ring liner, and for this purpose there is provided a receptacle 63 adapted to contain an adhesive or other cement material and provided with a drip spout 64, through which said adhesive is discharged very slowly. The receptacle 63 is carried upon a vertically slideable member 65 supported by a fixed bracket 66 and adapted for vertical movement therein. A downwardly projecting finger 67 carried by the receptacle support 65 is adapted to ride upon a cam surface 68 formed upon the upper face of the gear 21 in the peripheral region thereof. The action of said cam surface is such as to depress the adhesive receptacle 63 at the proper time in the revolution of the can end to cause the drip spout 64 to deposit a small amount of the adhesive upon the initial end portion of the ring liner placed within the flange of the can end 23. Thus when the final end of the liner strip is led within the can end flange and overlaps the initial end portion thereof, the two ends are secured together by the adhesive deposited upon said initial end portion. The adhesive receptacle 63 is understood to be held, by the mechanism described, free of the liner strip during the remainder of the rotation of the can end 23.

In the machine illustrated in the drawings, I have shown no means for placing the can end 23 upon its chuck and for retaining the same therefrom. It is understood that said end may be placed upon said chuck by hand or by any desired mechanism and may be similarly removed. I have shown an axially disposed spring pressed plunger 69 carried by the mandrel shaft 26 and adapted to bear against the can end to retain the same in position upon its chuck.

In the carrying out of the invention, a helix of liner material 25 is placed upon the mandrel 24. An unlined can end 23 is placed upon the chuck formed upon the upper surface of the gear 21. The end of the liner strip is led through the groove 31 in the fixed plate 28, around the beveled upper surface 32 of the gear 29 and the beveled flange

33 carried by the shaft 4, and under the feed roll 34. Said liner strip is then passed through the curved guide 38 and its end placed within the flange of the can end 23 under the presser roll 39. The mechanism 70 is then started by means of the clutch operating handle 13, and the can end is rotated and the liner strip automatically advanced by said mechanism as previously described. When the requisite length of liner strip has been fed, the knife 62 operates to cut the same. The continued motion of the parts of the machine thereafter places the remainder of the cut portion of the liner strip within the flange of the can ends 23, 80 the ends of said cut portion being glued together as above described. At the same time the uncut end of the liner strip is advanced by the feed roll 34 into position to be fed into the groove of the succeeding can 85 end. When the complete liner has been applied to the can end flange, and when the end of the uncut strip is in position for starting its application to the flange of the succeeding can end, the presser roll 39 is 90 raised free of the liner strip and the can end, and the mechanism automatically stops to permit the lined can end to be removed and an unlined end substituted therefor.

Having thus described my invention what I claim as new and desire to protect by Letters Patent is:—

1. The method of preparing flanged can ends for hermetic sealing to can bodies, which comprises placing within the flange of 100 a positioned can end a strip of fibrous liner material with the ends of the strip overlapping, and uniting said overlapping ends after the liner has been deposited onto the flange of the can end to form a continuous 105 gasket liner.

2. The method of lining flanged can ends for use in the hermetic sealing of food containers, which comprises positioning a strip of fibrous material relative to the flange 110 of a can end, cutting the said strip to cause the separated ends thereof to overlap, and uniting the adjacent ends of the said cut portion to form an endless ring liner when positioned onto the flange of the can end. 115

3. The method of preparing flanged can ends, having grooves for the reception of the can body flanges, for hermetic sealing with said body flange, which consists in applying the end of a strip of gasket material within 120 said groove, then progressively applying the following portions of said strip within the groove and causing the ends of said strip to overlap after they have been inserted within said groove, and uniting said ends to form a 125 ring liner or gasket.

4. The method of lining flanged can ends which comprises feeding a continuous strip of liner material into the flange of a can end, cutting said strip, and when said flange has 130

been completely lined, uniting the adjacent ends of the cut portion of said strip to form an endless ring liner within said flange.

5. The method of lining flanged can ends from a continuous strip of liner material which comprises cutting off a portion of said strip, placing the cut portion within the flange of a can end, and uniting the adjacent ends of said cut portion to form an 10 endless ring liner within said flange.

6. The method of lining flanged can ends

from a continuous strip of liner material which consists in feeding said strip from a helical coil, cutting off a portion of said strip, advancing said cut portion and placing the same within the flange of a rotating can end, and uniting the adjacent ends of said cut portion to form a ring liner within said flange. 15

In testimony whereof I affix my signature 20
hereto.

NICHOLAS A. ACKER.
